PLANTER BOWL

Lynn R. Townsend, 10707 Jamacha Blvd., Space 174,
Spring Valley, Calif. 92077

Filed Sept. 5, 1969, Ser. No. 19,041

Term of patent 14 years

Int. Cl. D31

U.S. Cl. D35—1

FIG. 1 is a side elevational view in perspective of the planter bowl showing my new design;

FIG. 2 is a top plan view of the planter bowl showing my new design;

FIG. 3 is a sectional elevational view taken along lines 3—3 of FIG. 2;

FIG. 4 is a sectional end elevational view taken along lines 4—4 of FIG. 2.

I claim:

The ornamental design for a planter bowl, substantially as shown.
